UNITED STATES PATENT OFFICE.

EDWIN J. AKINS, OF MOUNDSVILLE, WEST VIRGINIA.

OVERSHOE-HOLDER.

1,057,108.

Specification of Letters Patent. Patented Mar. 25, 1913.

Application filed July 3, 1912. Serial No. 707,492.

To all whom it may concern:

Be it known that I, EDWIN J. AKINS, a citizen of the United States of America, and resident of Moundsville, county of Marshall, and State of West Virginia, have invented certain new and useful Improvements in Overshoe-Holders, of which the following is a specification.

This invention relates to overshoe attaching means, and it has for its chief object to provide a simple and efficient device whereby an overshoe may be firmly attached to the shoe of a wearer and effectually prevented from pulling off.

15 A further object is to provide a neat appearing device of the character mentioned which has no part permanently attached either to the shoe or to the overshoe, which is of strong and durable construction, which 20 is adapted for application interchangeably to any of a plurality of shoes or overshoes that its owner may possess, and which does not injure or mar either the shoe or overshoe to which it is applied.

25 With these and other objects in view, the invention resides in the features of construction, arrangement of parts and combinations of elements which will hereinafter be fully described, reference being had to the accompanying drawings, forming a part of this specification, in which—

Figure 1 is a side elevation of the invention applied, the overshoe being shown in longitudinal section; Fig. 2 is a rear elevation of the same, the overshoe being shown in transverse section; and Fig. 3 is a side elevation of the invention detached.

Referring to said drawings, in which like designating characters distinguish like parts throughout the several views—1 indicates the opposite substantially parallel members of a substantially U-shaped clamp composed of sheet-metal, preferably spring steel, and adapted to closely embrace the heel portion 40 of a shoe-welt 2. Said members are inclined downward and each terminates in a horizontal line, as shown at 3, and has an in-turned ledge or flange 4 which is adapted to seat in the ordinary groove 5 located between the welt 2 and the heel 6 of the shoe.

50 In applying the device to the shoe, the members 1 are spread apart slightly beyond their normal disposition and are then permitted to spring back into shoe-gripping position with the flanges 4 closely seating in the groove 5 whereby a secure hold is se-

cured for positively preventing movement of the clamp in any direction other than in line with said groove.

Carried by, or formed integral with, the 60 clamp at its rearmost and uppermost part is a metal loop consisting of an upright member 7, which terminates at a suitable point in a return bend 8, and a return member 9 which lies substantially parallel to 65 said member 7, said members 7 and 9 being adapted to receive therebetween the upper edge of the rear portion of an overshoe 10. Pivotedly connected to the lower end of said member 9, which latter may be of any appropriate length, is a dog 11 having teeth 12 which, in one position of the dog, are adapted to firmly engage, or bite into, the material of the overshoe, as shown in Fig. 1. Formed integral with said dog and ar- 70 ranged at a suitable angle thereto is a lever 13 by means of which the dog is rotated on the pivot pin 14.

As is obvious, since the clamp is shaped to conform to the shoe and fits snugly thereon, no hindrance is thereby presented to the application of the overshoe. The overshoe itself holds the clamp against movement in the only direction in which it may move without the application of force, that is to 80 say, against horizontal movement; and, when the dog is caused to assume gripping or binding engagement with the overshoe, the latter is effectually held against displacement.

Having thus described my invention, what I claim as new, and desire to secure by Letters Patent, is—

1. An overshoe holder comprising a 95 spring-metal clamp adapted to fit over the rear part of a shoe above the heel, inturned horizontal flanges at the terminals of said clamp for seating in the groove between the heel and the welt, and overshoe engaging means carried by said clamp.

2. An overshoe holder comprising a 100 spring-metal clamp adapted to fit over the rear part of a shoe above the heel, inturned horizontal flanges at the terminals of said clamp for seating in the groove between the heel and the welt, and means carried by said clamp for gripping an overshoe.

3. An overshoe holder comprising a 110 spring-metal clamp adapted to fit over the rear part of a shoe above the heel, inturned horizontal flanges at the terminals of said clamp for seating in the groove between the

heel and the welt, and means carried by said clamp whereby an overshoe fitted over the shoe is held in fixed position against said clamp.

5. An overshoe holder comprising a spring-metal clamp adapted to fit over the rear part of a shoe above the heel, inturned horizontal flanges at the terminals of said clamp for seating in the groove between the heel and the welt, and a pivoted dog adapted to assume gripping engagement with an overshoe applied to said shoe.

10. An overshoe holder comprising a spring-metal clamp adapted to fit over the rear part of a shoe above the heel, inturned horizontal flanges at the terminals of said clamp for seating in the groove between the heel and the welt, a metal loop formed on said clamp for the reception of the upper edge of an overshoe, and means carried by said loop for gripping an overshoe.

15. An overshoe holder comprising a spring-metal clamp adapted to fit over the rear part of a shoe above the heel, inturned horizontal flanges at the terminals of said clamp for seating in the groove between the heel and the welt, a metal loop formed on said clamp for the reception of the upper

20. edge of an overshoe, and means carried by said loop for gripping an overshoe.

6. An overshoe holder comprising a spring-metal clamp adapted to fit over the rear part of a shoe above the heel, inturned

horizontal flanges at the terminals of said clamp for seating in the groove between the heel and the welt, a metal loop formed on said clamp for the reception of the upper edge of an overshoe, and a pivoted dog carried by said loop for clasping said overshoe 25 in fixed relation to said clamp.

7. An overshoe holder comprising a spring-metal clamp adapted to fit over the rear part of a shoe above the heel, inturned horizontal flanges at the terminals of said 30 clamp for seating in the groove between the heel and the welt, a metal loop formed on said clamp for the reception of the upper edge of an overshoe, and a pivoted dog carried by said loop and adapted to exert a 35 gripping pressure against an overshoe interposed between said dog and said clamp.

In testimony whereof I affix my signature in presence of two subscribing witnesses.

EDWIN J. AKINS.
